H. BLAIR.
MILK PAIL ATTACHMENT.
APPLICATION FILED APR. 30, 1920.

1,377,111.

Patented May 3, 1921.

UNITED STATES PATENT OFFICE.

HENRY BLAIR, OF SAN ARDO, CALIFORNIA.

MILK-PAIL ATTACHMENT.

1,377,111.

Specification of Letters Patent.

Patented May 3, 1921.

Application filed April 30, 1920. Serial No. 377,884.

To all whom it may concern:

Be it known that I, HENRY BLAIR, a citizen of Canada, residing at San Ardo, in the county of Monterey and State of California, have invented certain new and useful Improvements in Milk-Pail Attachments; and I do hereby declare the following to be a full, clear, and exact description of the invention, such as will enable others skilled in the art to which it appertains to make and use the same.

This invention relates to new and useful improvements in milk pail attachments and more particularly to brackets for supporting a bucket between the knees of a person while milking and has for its primary object the provision of means for securing the brackets to the bucket which will obviate any danger of said brackets becoming detached during use of the device and which will allow the easy and quick removal and replacement of the brackets on the bucket when desired.

Another object of this invention is the provision of a milk pail attachment of the above stated character, which shall be simple, durable and efficient, and which may be manufactured and sold at a comparatively low cost.

With these and other objects in view, as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:—

Figure 1 is a vertical sectional view illustrating a bucket or pail with brackets applied thereto and constructed in accordance with my invention,

Fig. 2 is a top plan view illustrating one of the brackets,

Fig. 3 is a detail sectional view illustrating the curvature of one portion of the bracket so as to conform to the contour of the pail or bucket,

Fig. 4 is a perspective view of an attaching member,

Fig. 5 is a similar view illustrating a wedge member.

Referring in detail to the drawing, the numeral 1 indicates a bucket or pail having

the usual bead 2 at its upper edge and to which my invention is applied. My invention consists of a pair of brackets 3 that are detachably secured at opposite points to the upper edge of the bucket or pail and are adapted to rest on a person's legs while sitting so that the bucket or pail is supported between the knees and in a position to be milked into. The brackets 3 are identical in construction and reference to one is thought sufficient for both. The bracket 3 consists of a vertical portion 4 and a horizontal portion 5. The vertical portion 4 is curved to conform to the contour of the inner face of the bucket or pail and bears flatly against the same with the horizontal portion overlying the bead 2 and projecting beyond said bucket or pail so that it can rest easily on a person's legs. The horizontal portion 5 is provided with spaced slots 6 to receive the arms 7 of a substantially U-shape attaching member 8, the bight portion of which overlies the horizontal portion 5 of the bracket. The ends of the arms 7 are bent at right angles to form bead engaging elements 9 that underlie the bead 2 as clearly shown in the drawing. A substantially U-shaped wedge member 10 has its arms 11 disposed in the slots 6 for preventing the arms 7 of the attaching member 8 from sliding in the slots away from the bead 2 of the bucket or pail. The bight portion of the wedge member 10 is bent upon itself to form a loop 12 to which is attached one end of a flexible element 13. The flexible element 13 has its other end attached to a staple or loop 14 secured to the vertical portion 4, so as to obviate the danger of the wedge member 10 from becoming detached or lost from the brackets during the use and non-use of the device.

From the foregoing description taken in connection with the accompanying drawing, it will be noted that a device has been provided which can be easily and quickly applied to a bucket or pail and also is capable of adjustment so that it can be applied to pails or buckets having different shaped beads and of different sizes. Also it is to be noted that the device can be easily and conveniently removed from the buckets or pails by simply removing the wedge member and sliding the locking member in the slots.

While I have shown and described the preferred embodiment of my invention, it will be understood that minor changes in

construction, combination, and arrangement of parts may be made without departing from the spirit and scope of the invention as claimed.

5 Having thus described my invention, what is claimed is:—

1. A milk pail attachment comprising a pair of brackets each including vertical and horizontal portions, said vertical portion enclosing the pail on its inner face and having the horizontal portion overlying the bead of the pail and projecting laterally thereof, said horizontal portions having spaced slots, a substantially U-shaped fastening member 10 extending through said slots and having its ends bent at right angles to underlie the bead, and means extending through the slots for holding the ends of said fastening member in engagement with the bead.
- 15 2. A milk pail attachment comprising a pair of brackets each including vertical and horizontal portions, said horizontal portion having spaced slots, a substantially U-shaped fastening member extending through said

slots and having its ends bent at right angles to underlie the bead of a pail, and a substantially U-shaped wedge member extending through said slots.

3. A milk pail attachment comprising a pair of brackets secured to the opposite sides of the pail and each including vertical and horizontal portions, said horizontal portion having spaced slots, a substantially U-shaped member extending through said slots and having its ends bent at right angles to 30 underlie the bead of the pail, a substantially U-shaped wedge member extending through said slots and having its right portion bent to form a loop, a flexible element connected to said loop, and a staple secured to the vertical portion and having the free end of the flexible element secured thereto.

In testimony whereof I affix my signature in presence of two witnesses.

HENRY BLAIR.
